(57) **CLAIM**

The ornamental design for thermometer with probe and probe cover, as shown and described.

DESCRIPTION

FIG. 1 shows a perspective view of the front side of the thermometer and probe.

FIG. 2 shows a front view of the thermometer and probe.

FIG. 3 shows a back view of the thermometer and probe.

FIG. 4 shows a first side view of the thermometer and probe.

FIG. 5 shows a second side view of the thermometer and probe.

FIG. 6 shows a bottom view of the thermometer.

FIG. 7 shows a top view of the thermometer.

FIG. 8 shows a perspective view of the thermometer and probe cover.

FIG. 9 shows a front view of the thermometer and probe cover.

FIG. 10 shows a back view of the thermometer and probe cover.

FIG. 11 shows a first side view of the thermometer and probe cover.

FIG. 12 shows a second side view of the thermometer and probe cover.

FIG. 13 shows a bottom view of the thermometer and probe cover; and,

FIG. 14 shows a top view of the thermometer and probe cover.

The article is shown with a symbolic break in its length. The appearance of any portion of the article between the break lines forms no part of the claimed design.

1 Claim, 6 Drawing Sheets
